UNITED STATES PATENT OFFICE.

PHILIP J. HAAS, OF YORK, NEBRASKA.

REINFORCED-CONCRETE POST.

937,794.

Specification of Letters Patent. Patented Oct. 26, 1909.

Application filed August 25, 1908. Serial No. 450,167.

To all whom it may concern:

Be it known that I, PHILIP J. HAAS, citizen of the United States, residing at York, in the county of York and State of Nebraska, have invented certain new and useful Improvements in Reinforced-Concrete Posts, of which the following is a specification.

The present invention relates to improvements in posts, and more particularly to that type of posts which are formed of concrete, cement, artificial stone, or other like material which is molded into shape when in a plastic condition and permitted to set, after which it becomes hard and solid.

The object of the invention is the provision of a novel means for reinforcing the post whereby the reinforcing members are brought fully into play as soon as the post is subjected to a bending strain and will not stretch a sufficient amount to permit of the post cracking.

For a full understanding of the invention and the merits thereof and also to acquire a knowledge of the details of construction and the means for effecting result, reference is to be had to the following description and accompanying drawings, in which:

Figure 1 is a perspective view of a post embodying the invention, portions being broken away, Fig. 2 is an enlarged horizontal sectional view on the line 2—2 of Fig. 1, Fig. 3 is an enlarged detail perspective view of one of the nuts.

Corresponding and like parts are referred to in the following description and indicated in all the views of the drawings by the same reference characters.

Specifically describing the present embodiment of the invention the numeral 1 designates the body portion of the post which is formed of some plastic material such as concrete. Embedded in opposite ends of the body portion 1 are the tension nuts 2 which are provided with the centrally disposed threaded openings 2^a and also with the side openings 2^b which are designed to receive the concrete or plastic material so as to prevent rotation of the tension nuts and secure a firm bond between the same and the body portion of the post. In the present instance these nuts are rectangular in shape and are provided upon opposite edges with the notches 3, the said notched edges being curved inwardly so that the inner and opposing faces of the nuts are concaved while the outer faces are convexed.

Extending longitudinally through the body portion of the post and embedded therein are the loops 4 of reinforcing wire, the ends of the endless loops being passed around the nuts 2 and caused to engage the notches 3 by means of which the wires are held in proper position while the post is being molded and previous to the hardening of the same.

The posts are designed to be formed in a mold similar to that disclosed in my co-pending application for patent filed the 28th day of April 1908, Serial No. 429,679, the ends of the mold being provided with bolts 70 which engage the threaded openings 2^a of the nuts. By turning these bolts the nuts at opposite ends of the post can be drawn apart and the wire loops 4 placed under a high tension. These wires are thus held in 75 a stretched position by means of the bolts until the plastic material has become thoroughly hardened when the bolts are disengaged from the nuts, the said nuts being held in position by the hardened body portion of the post and the wires remaining under tension. With this construction the reinforcing wires are immediately brought into full play as soon as the post is subjected to a bending strain and the wires will 85 not stretch a sufficient amount to permit cracking of the post as is frequently the case where they are embedded in the post without being placed under tension.

Having thus described the invention, what 90 is claimed as new is:

1. In a post, the combination of a body portion formed of plastic material, tensioning nuts embedded in the opposite ends of the body portion and supported entirely by 95 the plastic material of the said body portion, and endless reinforcing loops also embedded in the body portion and passing around the tensioning nuts, the said reinforcing loops being placed under an initial 100 tension before the plastic material has hardened.

2. In a post, the combination of a body portion formed of plastic material, tensioning nuts embedded in opposite ends of the 105 post, and reinforcing loops passing around the nuts and acting under a high tension, the outer faces of the nuts being convexed to admit of the loops slipping around the same and adjusting themselves previous to 110 the hardening of the plastic body portion.

3. In a post, the combination of a body

portion formed of plastic material, tensioning nuts embedded in opposite ends of the body portion, the said nuts being formed with openings for receiving the plastic material to obtain a firm bond therewith, and the edges of the nuts being notched, and endless reinforcing loops extending around the nuts and engaging the notches whereby

they are held in proper position, the said reinforcing loops acting under a high tension. 10

In testimony whereof I affix my signature in presence of two witnesses.

PHILIP J. HAAS. [L. S.]
